(57) **CLAIM**

The ornamental design for a flexible power connector for type A sockets, as shown and described.

DESCRIPTION

FIG. 1 is a perspective view of the flexible power connector for type A sockets showing our new design;

FIG. 2 is a front view thereof;

FIG. 3 is a back view thereof;

FIG. 4 is a top view thereof;

FIG. 5 is a right side view thereof, the left side being a mirror image; and,

FIG. 6 is a bottom view thereof.

The flexible power connector is shown with a symbolic break in its length. The appearance of any portion of the article beyond the break line forms no part of the claimed design. The broken lines in the drawings represent unclaimed environment only and form no part of the claimed design.
